[57] **CLAIM**

The ornamental design for the clip on device for locking touch tone telephones, as shown and described.

DESCRIPTION

FIG. 1 is a partial perspective view of the front, right side and top of the clip on device for locking touch tone telephones, with the back of a telephone receiver shown in dash lines for purposes of illustration including one position where said device may be mounted on a telephone;

FIG. 2 is a left side view of the clip on device shown in FIG. 1;

FIG. 3 is a bottom plan view of the clip on device shown in FIG. 1;

FIG. 4 is a top plan view of the clip on device shown in FIG. 1; and

FIG. 5 is a perspective view of the left side and bottom of the clip on device shown in FIG. 1.
